UNITED STATES PATENT OFFICE.

JOHN G. DECKER, OF STROUDSBURG, PENNSYLVANIA.

ELECTRIC-LINE-WIRE INSULATOR.

1,382,483.

Specification of Letters Patent. Patented June 21, 1921.

Application filed May 24, 1918. Serial No. 236,343.

To all whom it may concern:

Be it known that I, JOHN G. DECKER, a citizen of the United States, residing at Stroudsburg, in the county of Monroe and

5 State of Pennsylvania, have invented certain new and useful Improvements in Electric-Line-Wire Insulators, of which the following is a specification.

This invention relates to insulators, and 10 pertains especially to the class of insulators applicable to telegraph, telephone and trolley wires.

The object of the invention is to provide an insulating device of such novel and peculiar construction as to afford expeditious means for applying electric wire thereto and for holding the wire therein without twisting or bending the wire from straight condition either in applying or holding the 20 wire.

A further object of the invention is to provide a wire insulating device having the usual screw socket applicable to the cross-bars of telegraph, telephone and trolley 25 posts, and having a solid spherical head, and a peculiarly shaped channel or groove between the head and the socket for introducing and holding an electric wire free to be drawn lengthwise and to be removed 30 through the groove by lateral movement of the wire in the groove or wire passageway.

A still further object of the invention is to provide an insulator of this character with an annular tie wire groove adjacent 35 to the head of the insulator, and a similar groove adjacent to the bottom or lower end of the insulator, so that the insulator may be used as an anchor in stretching or repairing the line wire, or at intervals throughout the line as a tie post.

Various other objects, advantages and improved results are attainable in the practical manufacture and application of the invention.

45 In the accompanying drawings forming part of this application:

Figure 1 is an elevation of the insulator.

Fig. 2 is a sectional view taken on the dotted line A—A, Fig. 1.

50 Fig. 3 is a cross section taken on the dotted line B—B, Fig. 1.

Fig. 4 is a similar view taken on the dotted line C—C, Fig. 1.

55 Fig. 5 is an elevation of a modification partly broken away.

The same reference characters denote the same parts throughout the several views of the drawings.

In practical application of insulators of this character, which are usually composed 60 of glass, porcelain or similar material, it is well known that they are subject to contraction and expansion under varying weather conditions; therefore, it is essential to provide an insulator in avoidance of such contraction and expansion as far as possible, 65 and yet of such construction as to permit the insertion and removal of a line wire, and for holding the wire for free longitudinal movement, and so that the wire may 70 have sufficient play in the insulator as to prevent breaking of the wire-holding part of the insulator. It is also essential that provision be made to avoid turning, twisting and bending the wire in placing, holding 75 and removing it with respect to the insulator, so that the wire may be quickly and expeditiously slipped into proper position.

In carrying out my invention I employ 80 the usual glass or porcelain insulator having a solid conical or spherical head member 1, a body portion 2, having the usual base comprising annular flanges 3 and 4 with a groove 5 therebetween, and the body portion 2 is provided with the ordinary screw 85 socket 6 adapted to fit screw pins on cross-heads of telegraph, telephone and trolley posts of common use, or the insulator may be applied to the end of such posts as usual. 90

The essential feature of the invention consists in forming a peculiarly shaped passage 95 for lateral movement of the line wire 7 into and out of a peculiarly shaped central holder. Said passage is formed by a continuous serpentine-like groove or slot having parallel walls extending straight through the spherical head member 1, so as to avoid twisting, indenting or bending the line wire 7 therein or thereby. Said passage starts with a mouth 8 in the side of the head member 1, and preferably adjacent to the body portion 2 of the insulator for the entrance and exit of the wire 7. The upper lip 9 of the mouth 8 overhangs the lower lip 10 enough to protect the mouth from collecting any drippings or other elements which may fall from the head member 1. A passage member 11 extends downwardly and inwardly from the mouth 8 to a shoulder 12, another passage member 13 extends from the 110

shoulder 12 upwardly into the head member, and an arc-shaped passage member 14 extends downwardly from the passage member 13 to a vertical elongation or seat 15 located 5 centrally of the intersection of the head member and the body member. A solid portion 16 is formed centrally over the seat and is connected with the body member by a neck 17. Said passage members, which 10 constitute the line wire slot, form a shoulder 18 adjacent to and opposite a shoulder 19 of the seat 15. The elongated seat is such as to permit vertical movement of the line wire without displacement. Obviously, the 15 wire 7 must be pulled or pushed laterally over the said shoulders in placing and removing the wire with respect to its elongated seat 15. The solid center 16 directly over the wire seat with the thick neck 17 constitute 20 a substantial abutment for the upper thrust of the line wire, and said center and neck are not subject to fracture on account of contraction and expansion, or by manipulation of the wire, or from accidental 25 dropping or contact with foreign objects. A sagging or slack wire has a solid support in the material between the socket 6 and the seat 15.

The above described insulator is for use 30 on a series or multiple of posts intervening tie or terminal posts, but the same insulator may be used as an anchor or on tie or terminal posts by applying a tie wire to the semi-circular groove 20 extending from one end 35 to the other of the wire seat 15, and twisting the tie wire around the line wire to hold the latter fixed to the insulator during splicing or repairing the line wire.

The insulator is provided with a circular 40 groove 21 adjacent to the bottom thereof for tying the wire when the latter is to be run at an angle or diagonally, and the location of this groove relative to the lower end of the insulator is important, in that the wire 45 pull is close to the large end of the socket stem and adjacent to the post, thereby avoiding the usual likelihood of fracture or breaking off of the screw stem under the strain of wire stretching. This is an important feature 50 of the device for preserving the screw pins or stems.

Referring to Fig. 5, a modified groove or

wire passage 22 is shown, having a curved mouth 23, a shoulder 24 above the horizontal plane of the wire seat or elongation 25, and 55 the parallel walls of this passage are in serpentine or compound curves extending straight through the spherical head 26 to opposite sides thereof.

It will be understood that there is no tying 60 of the line wire to the series of intermediate insulators throughout a telegraph or telephone line, whereby the expense of tie wire and the time and labor of applying it is avoided.

It will also be observed that the liability 65 of accidental displacement of the line wire with respect to the insulator is avoided; that said wire has ample play in the elongated seat for lengthwise movement and stretching, and that the insulator is not weakened 70 by reason of the wire slot and grooves therein.

I do not wish to be understood as confining 75 my invention to any particular size or insulating material, nor to the particular angle and location of the entrance and exit passage, but I reserve the right to make such changes and variations in the manufacture 80 and practical application of the invention as may come within the scope of the appended claim.

Having thus described my invention, what I claim as new and desire to secure by Letters Patent is:

A device of the type described comprising 85 an insulator of the electric line-wire type, the body portion of said insulator having a wire-receiving passage extending transversely therethrough and of continuous serpentine-like outline, starting with a mouth 90 in the side of the head of said body-portion, the upper lip overhanging the lower lip of said mouth and including a downward extension reversely upwardly curved and 95 again reversely curved upwardly and finally extending vertically downward, forming a seat for the line-wire.

In witness whereof I hereunto set my hand in the presence of two witnesses.

JOHN G. DECKER.

Witnesses:

V. S. LODER,
E. E. MICHAELS.
